UNITED STATES PATENT OFFICE.

AUGUST G. KREIMER, OF CINCINNATI, OHIO.

CRUTCH.

SPECIFICATION forming part of Letters Patent No. 761,506, dated May 31, 1904.

Application filed June 3, 1903. Serial No. 159,898. (No model.)

To all whom it may concern:

Be it known that I, AUGUST G. KREIMER, a citizen of the United States, residing at Cincinnati, in the county of Hamilton and State of Ohio, have invented certain new and useful Improvements in Crutches, of which the following is a specification.

The object of my invention is to provide an improved crutch which will yield to the weight of the body, thus relieving the jar of walking, which will not slip from under the user to cause falls, and which is of simple and durable construction.

My invention consists in the combination and arrangement of parts hereinafter described and claimed.

In the drawings, Figure 1 is a sectional side elevation of the lower portion of a crutch embodying my invention; Fig. 2, an end view of Fig. 1; Fig. 3, a section on line 3 3 of Fig. 1, and Fig. 4 a bottom plan view of the ground-piece of the crutch.

To the lower ends of the crutch standards or legs A is secured a frame-piece B, in which is pivotally mounted a reversible ground-piece C. The piece C is preferably mounted on screws c, having shoulders c', which, taking against corresponding shoulders in piece C, permit tightening of screws c without binding on their bearings b in frame B. A longitudinal rib c² is provided at one side of piece C, and a spring-held clamp b' with jaws b² is pivoted to frame B, so as to engage rib c² and lock-piece C in either of its reversible positions. At either end piece C is provided with a cap D, secured to piece C by a threaded plug d taking into a threaded socket c³ in piece C. A nut d' on cap D facilitates the removal or replacement of cap D. The plug d and cap D are bored to permit the free passage of screws E and E', which are yieldingly held in position by rubber blocks e and e' in the bottom of sockets c³. Each of the screws E and E' serves to secure a square rubber block or pad F to the outer ends of piece C. A larger square rubber block or pad G is provided with a square central opening adapted to fit snugly over block F, where it is held against cap D by its frictional engage-

ment with block F. The screw E in the end 50 of the floor-piece designed for outdoor use is made long enough to protrude from block F and is held in position by two rubber blocks e, while the other or indoor end is provided with a shorter screw E' and but one rubber 55 block e' to hold the screw in position.

In use out of doors the point of screw E engages with the ground or ice or snow to prevent slipping. When the weight of the body is thrown on the crutch, the screw E yielding 60 against the rubber blocks e relieves the jar. In case the point of screw E should strike a hard smooth surface, such as a pebble or wet asphalt, and slip or tend to slip the yielding of screw E and the angle which the crutch 65 assumes in slipping will bring one side of rubber pads F and G into contact with the ground and prevent further slipping. This result is facilitated by the opening of the joint between blocks F and G on the contacting side, which 70 presents the sharp edge g of the central opening in pad G to the ground. The pressure of block G on cap D forms an annular recess in the inner face of the block, so that when the block is reversed, as may easily be done, the 75 outer face is slightly cupped in the center, which further tends to prevent slipping by suction. When the outer one of the rubber blocks e becomes worn or loses its elasticity, it may readily be replaced without disturbing 80 the inner block.

In use indoors the ground-piece C is reversed and the weight borne directly by rubber blocks F and G, as screw E' does not protrude. The action of the rubber blocks is 85 substantially the same as when they contact on the outdoor side to prevent slipping. They also relieve the jar in walking. Here the yielding of screw E' tends to relieve the jar of walking and by permitting the screw to 90 follow rubber block F prevents the wearing loose of the threads in the block.

While I have shown and described the preferred means for carrying my invention into effect, this is capable of variation without departing from the spirit of the invention. I therefore do not wish to be confined to the exact construction disclosed; but

What I claim as new, and desire to secure by Letters Patent, is—

1. In a crutch, the combination of a rubber ground-pad; a screw securing the pad in position and capable of longitudinal movement; and a larger rubber ground-pad having a central opening adapted to take over the first pad and be held in position by frictional engagement therewith, substantially as specified. 30
2. In a crutch, the combination of a ground-piece; a threaded socket in the ground-piece; a bearing-cap having a threaded plug adapted to take into the socket; a screw taking through the cap and plug and capable of longitudinal movement therein; a rubber block in the socket behind the head of the screw; a rubber pad secured to the end of the screw; and a larger rubber pad having a central opening adapted to take over the first pad and be held in position by frictional engagement therewith, substantially as specified. 35
3. In a crutch the combination of a rubber ground-pad; a screw, capable of longitudinal movement, securing the pad in position and protruding from the face of the pad to contact with the ground; and a larger rubber pad having a central opening adapted to take over the first pad and be held in position by frictional engagement therewith, substantially as specified. 40
4. In a crutch, the combination of a reversible ground-piece; a rubber ground-pad secured to one end of the ground-piece by means of a screw capable of longitudinal movement; and a rubber ground-piece secured to the other end of the ground-piece by means of a screw capable of longitudinal movement and protruding from the face of the pad, substantially as specified. 45
5. In a crutch, the combination of a reversible ground-piece; a rubber ground-pad secured to one end of the ground-piece by means of a screw capable of longitudinal movement; a rubber ground-piece secured to the other end of the ground-piece by means of a screw capable of longitudinal movement and protruding from the face of the pad; and larger rubber ground-pads having central openings adapted to take over the first pads and be held in position by frictional engagement therewith, substantially as specified. 50
